Fig. 15.

*Fig. 16.**Fig. 17.**Fig. 18.*FIGURE 1 is a side elevational view of a first embodiment of a bicycle, showing my new design;

FIGURE 2 is a top plan view thereof;

FIGURE 3 is a front elevational view thereof;

FIGURE 4 is a side elevational view of a second embodiment of a bicycle showing my new design;

FIGURE 5 is a top plan view thereof;

FIGURE 6 is a front elevational view thereof;

FIGURE 7 is a side elevational view of a third embodiment of a bicycle showing my new design;

FIGURE 8 is a top plan view thereof;

FIGURE 9 is a front elevational view thereof;

FIGURE 10 is a side elevational view of a fourth embodiment of a bicycle showing my new design;

FIGURE 11 is a top plan view thereof;

FIGURE 12 is a front elevational view thereof;

FIGURE 13 is a side elevational view of a fifth embodiment of a bicycle showing my new design;

FIGURE 14 is a top plan view thereof;

FIGURE 15 is a front elevational view thereof;

FIGURE 16 is a side elevational view of a sixth embodiment of a bicycle showing my new design;

FIGURE 17 is a top plan view thereof; and

FIGURE 18 is a front elevational view thereof.

The dominant features of my design reside in the por-

2, 3, 5, 6, 8, 9, 11, 12, 14, 15, 17 and 18 have been omitted for convenience of illustration.

This application is a continuation of the following applications:

Ser. No. D. 71,321, filed August 16, 1962; Ser. No. D. 71,322, filed August 16, 1962; Ser. No. D. 71,323, filed August 16, 1962; Ser. No. D. 71,362, filed August 16, 1962; Ser. No. D. 71,668, filed September 12, 1962; Ser. No. D. 71,669, filed September 12, 1962, and now abandoned.

I claim:

The ornamental design for a bicycle, substantially as shown and described.
